TYPOGRAPHICAL COMPOSING MACHINE

Christian Augustus Albrecht, Berlin, Germany,
assignor to Mergenthaler Linotype Company,
Brooklyn, N. Y., a company of New York

Application January 6, 1936, Serial No. 57,865
In Germany January 29, 1935

5 Claims. (Cl. 199—18)

This invention relates to typographical composing machines, such as those known commercially under the registered trade-mark "Linotype", wherein key-controlled mechanism effects the release of matrices from a magazine, for composition in line. For the production of spaced-out lines in such machines, it has been proposed to provide for the release of a space matrix conjointly with the release of a character matrix, through the actuation of the mechanism for controlling the release of the character matrix, by coupling the character-matrix escapement reeds with a space-matrix escapement reed. In this known arrangement, however, the space matrices are always released from the same space-matrix channel of the magazine, which may be so quickly emptied as to render the operation of the coupling device ineffective.

The invention overcomes this difficulty by enabling space matrices to be drawn from a number of magazine channels when the coupling device is in operation, and to this end, according to the invention, a plurality of groups of character-matrix releasing devices are connected with a corresponding plurality of space-matrix releasing devices, one of the latter being associated with each group, the coupling device being arranged to connect the character-matrix releasing devices of each group with the respective space-matrix releasing device.

One constructional form of the invention is illustrated in the accompanying drawing, which shows in vertical section, the relevant parts of a key-controlled matrix releasing mechanism.

The mechanism illustrated is generally of known form comprising key levers *a* which engage the keyboard bars *b* arranged in a row at the rear of the keyboard; trip dogs *c* actuated by the raising of the keyboard bars when the key levers are depressed; cam yokes *d* released by the actuation of the trip dogs *c*; continuously rotating rollers *f* with which cams *e* carried by the yokes *d* engage when the yokes are released, and escapement reeds *g* moved upwardly to actuate the magazine escapements (not shown) when the yokes *d* are raised by the action of the rollers *f* on the cams *e*.

According to the constructional form of the invention shown in the drawing the keyboard bars *b* are provided with rearwardly extending lugs *h*, and comprise four groups distinguished by the level at which the lugs *h* are located on the bars of the respective groups. Each group

conveniently consists of one-fourth of the total number of the keyboard bars employed for the release of character matrices, and the four groups have their lugs located respectively in the positions indicated at *h*, *h*¹, *h*² and *h*³.

This arrangement is appropriate to the release of space matrices from four different magazine channels, and for this purpose each keyboard bar employed for the release of space matrices is provided with a lug *i* which is formed like the lugs *h* inverted so that corresponding lugs *h* and *i* have their horizontal edges facing each other with a free space between them. The lugs on the four space-matrix releasing keyboard bars are arranged at respectively different levels, indicated at *i*, *i*¹, *i*², *i*³, corresponding with the levels of the lugs *h*, *h*¹, *h*², *h*³, of the different groups of character-matrix releasing keyboard bars.

In guides *m* behind the keyboard bars there is mounted a carriage *n* which can be moved forwardly and backwardly by means of a handle *o*. In the said carriage, lever arms *q* carrying rails or bails *r* are pivoted on studs *p*. In their normal position, as illustrated in the drawing, these lever arms *q* are held against stops *t* by means of springs *s*.

The mode of operation of the above-described arrangement is as follows. When the carriage *n* is in the inoperative position shown in the drawing, the keyboard mechanism operates in the usual manner, but, when the carriage *n* is moved forwardly by means of the handle *o*, the four bails *r* are located above the lugs *h*, *h*¹, *h*², *h*³, of the respective groups of character-matrix releasing keyboard bars, and below the lugs *i*, *i*¹, *i*², *i*³, of the corresponding space-matrix releasing bars. Thus, when a keyboard bar having a lug at the level *h* is actuated by the striking of the connected key, the bail *r* at that level will be turned upwardly about the stud *p* and will carry with it the respective space-matrix releasing keyboard bar, by engagement with the lug *i*. A corresponding action takes place when a keyboard bar of any of the other three groups is actuated through the co-operation of the related bail *r*, lugs *h*¹, *h*², or *h*³ and lugs *i*¹, *i*², *i*³.

The distance between the horizontal operative surfaces of the lugs *h* and *i*, *h*¹ and *i*¹, etc., is arranged so that the release of the space-matrices is slightly delayed to ensure that the latter reach the line in all cases after the character matrices are delivered. A corresponding delay could also be provided for in a manner

heretofore proposed, by altering the shape of the keyboard cams for the space matrices.

The striking of character keys of the different groups thus results in the release of space matrices from different magazine channels, and a shortage of space matrices is avoided.

The constructional form of mechanism above described has been chosen as a convenient example, and it will be understood that modifications in the form and mode of operation of the parts may be made without departing from the invention. For instance, the bails *r* might be brought into and out of operative position by a pivotal instead of a sliding movement, and the number of the space-matrix channels employed, and consequently the grouping of the character-matrix releasing keyboard bars, may be varied to suit particular requirements. Further, recesses in the keyboard bars could be provided in place 20 of the before-described lugs thereon.

It will be understood that the space matrices herein referred to may be any of the blank matrices used in the commercial machines and known as em or en quads or thin spacers. As 25 heretofore stated, it is common practise (especially in connection with foreign languages) to compose these space matrices between letter matrices in order to produce a spaced out line. The regular expansible spacebands will be composed between words as ordinarily, unless the 30 nature of the work is such as to call for blank matrices even for word spacing in which case such blank matrices will be released by means of the regular keys provided for the purpose.

35 Having described my invention, I declare that what I claim and desire to secure by Letters Patent is:—

1. In a typographical composing machine, the combination of a plurality of space-matrix releasing devices, a corresponding plurality of groups of character-matrix releasing devices, and means associated with each such group and with a respective space-matrix releasing device adapted to effect the actuation of said space-matrix 45 releasing device through the actuation of any one of the character-matrix releasing devices of the respective group.

2. In a typographical composing machine, the

combination of a plurality of space-matrix releasing devices, a corresponding plurality of groups of character-matrix releasing devices, motion transmitting means associated with each such group and with a respective space-matrix releasing device adapted to effect the actuation of said space matrix releasing device through the actuation of any one of the character-matrix releasing devices of the respective group, and means adapted to render said motion transmitting 10 means operative and inoperative at will. 5

3. In a typographical composing machine, the combination of a plurality of space-matrix releasing keyboard bars, a group of character-matrix releasing keyboard bars appropriate to each 15 space-matrix releasing keyboard bar, a bail appropriate to each such group adapted to connect the bars thereof with the respective space-matrix releasing keyboard bar, and means adapted to render the bails operative and inoperative at will. 20

4. In a typographical composing machine, the combination of a plurality of groups of keyboard bars, each of which groups comprises one space-matrix releasing bar and a plurality of character-matrix releasing bars, shoulders on the bars of 25 each group located at one level different from the level of those on the other groups, a bail appropriate to each group located at the level of the shoulders on the bars of the respective group, and means adapted to move the bails into and out 30 of engaging relationship with the said shoulders.

5. In a typographical composing machine, the combination of a plurality of groups of keyboard bars, each of which groups comprises one space-matrix releasing bar and a plurality of character-matrix releasing bars, shoulders on the bars of 35 each group located at one level different from the level of those on the other groups, a plurality of bails one appropriate to each group of keyboard bars, superposed pivoted levers on which said 40 bails are carried at levels corresponding to the levels of the shoulders on the keyboard bars of the respective groups, a carriage supporting said levers, and means adapted to adjust said carriage to bring the bails into and out of engaging relationship with the said shoulders. 45

CHRISTIAN AUGUSTUS ALBRECHT.
